Attorney.

UNITED STATES PATENT OFFICE.

JOHN J. NOLAN, OF BROOKLYN, NEW YORK.

ATTACHMENT FOR DRILLING OR REAMING CHANNELLED BARS, ANGLE-IRONS, &c.

SPECIFICATION forming part of Letters Patent No. 793,146, dated June 27, 1905.

Application filed March 19, 1904. Serial No. 198,962.

To all whom it may concern:

Be it known that I, JOHN J. NOLAN, a citizen of the United States, residing in the borough of Brooklyn, in the county of Kings and State 5 of New York, have invented a new and useful Improvement in Attachments for Drilling or Reaming Channeled Bars, Angle-Irons, and the Like, of which the following is a specification.

10 It has heretofore been the practice for the most part in structural-iron work involving the assembling of angle-irons, channeled bars, and the like to drill the holes therein prior to the assembling and thereafter to assemble the 15 same by means of bolts, rivets, or other fastening devices. It frequently happens, however, that the holes in the parts when drilled prior to assembling are found when assembled to be slightly out of alinement, owing to the 20 expansion of the metal, to careless workmanship, or for other reasons; and the object of my present invention is to devise a light, compact, and easily-set-up appliance whereby the juxtaposed holes in the various classes of 25 structural-metal work can be readily reamed, so as to correspond in position.

To the above ends my invention consists of a novel construction of drilling or reaming attachment for use in places inaccessible to 30 drills or reamers of the usual or ordinary construction.

It further consists in a novel construction of bracket for supporting drilling or reaming apparatus and in means for readily detaching 35 or disconnecting the same at the desired point.

It further consists of novel features of construction, all as will be hereinafter set forth.

Figure 1 represents a side elevation of my 40 drilling or reaming apparatus embodying my invention. Fig. 2 represents a perspective view of the supporting-bracket employed, the same being shown in detached position. Fig. 3 represents a sectional view of a portion of structural-metal work after having been 45 reamed by my invention. Fig. 4 represents a partial sectional view and partial side elevation of certain of the parts seen in Fig. 1, the same being on a reduced scale. Fig. 5 represents a sectional view of a portion of structural work, showing the position of the rivet 50

therein in case my invention had not been applied thereto. Fig. 6 represents a section on line $\alpha\alpha$, Fig. 5.

Similar numerals of reference indicate corresponding parts in the figures. 55

Referring to the drawings, 1 designates a spindle having a flattened portion or tongue 2, which is adapted to be engaged by the chuck 3 of any of the well-known rotary motors so universally employed at the present 60 time, as compressed-air motors, for drilling, reaming, or other purposes.

The spindle 1 is rotatably mounted in the sleeve 4, which forms a bearing for said spindle and which is secured in the opening 5 of the boss 6, which depends from the bracket 7, which consists of the plate 8, having the laterally-projecting members 9 and the upwardly-projecting portions 10, through which pass the set-screws 11, which are adapted to 70 engage a strip 12, which bears upon the inner surface of the angle-iron or channel-bar 13.

14 designates a set-screw passing through the member 9 of the bracket 7 and adapted to engage the strip 15, which contacts with the 75 under side of the flange or member 13, it being understood from Fig. 2 that the members 9 and 10 are preferably constructed in pairs.

The upper part of the plate or body portion 8 is provided with the ears 16, having 80 holes 17 therethrough, in which is located the shaft 18, upon which the cam member 19 is mounted or constructed, said cam being operated by means of the handle 20.

The sleeve 4 has the arm 21 projecting there- 85 through, in the upper portion of which is a bearing for the gear 22, which latter is thereby offset from the line of the spindle 1. The gear 22 carries or has attached thereto the reamer, drill, or other implement 23, said 90 gear 22 being operated by means of the gear 24, which is carried upon the extremity of the spindle 1, it being apparent that the spindle, gears 24 and 22, and the reamer or other tool 23 rotate in unison upon the application of 95 power to the bit or tongue 2. The gear 22 may be held in position with respect to its bearing by the arm 21 by any suitable means; but I preferably show the same as formed 100 with an extension 25, which serves as a bear-

ing and has the threaded portion 26, upon which the nut or collar 27 is screwed, whereby the parts are readily held in assembled position.

5 In Figs. 1 and 5 I have shown my device as applicable to a channel-bar, consisting of the web 28, having the flanges 29 and 13. The bracket 7 is readily attached to one of the flanges, as 13, by means of the set-screws 11 10 and 14, and is held in position by the proper manipulation of the cam 19, which is effected by the handle 20.

In Figs. 1, 5, and 6 I have shown the position which the parts are liable to assume if assembled and riveted without the alining holes being first reamed according to my improvement. It will be apparent, however, that the parts being in the position shown in Fig. 1 and a compressed-air motor of suitable construction being applied to the bit 2 and the spindle 1 being caused to rotate and pressure being imparted thereto in the direction of the arrow *a* the spindle 1, the gears 24 and 22, and the reamer 23 will be simultaneously rotated 25 and advanced and the riveted holes in the contiguous members 29, 30, and 31 will be reamed so as to appear as seen in Fig. 3, whereupon the rivet can thereafter be readily headed and secured in position.

30 It will of course be understood that the sleeve 4 is provided with a groove with which engages the spline 32 in the hub 6, whereby the sleeve 4 and its adjuncts may be advanced or retracted, as desired. It will also be seen 35 that by reason of the adjustability of the set-screws 14 and of the cam 19 the device may have a slight vertical adjustment to properly center the tool 23 in the holes to be reamed.

It is evident that by the word "drill" or 40 its equivalent wherever used I include a reamer of any desired form, as, indeed, the attachment will largely be used with the latter tool. It is also clear that a countersink may be substituted for the drill or reamer 45 whenever required.

It is evident that various changes may be made by those skilled in the art which will come within the scope of my invention, and I do not, therefore, desire to be limited in every 50 instance to the exact construction herein shown and described.

Having thus described my invention, what I claim as new, and desire to secure by Letters Patent, is—

55 1. A drilling attachment comprising a rotary spindle, a bearing in which said spindle is mounted, an offset on said bearing, intermeshing gears mounted on said spindle and in said offset and tool-receiving means operatively 60 connected with the offset gear in combination with supporting means in which said bearing is longitudinally movable.

2. In a drill attachment, the combination of a rotary spindle, a bearing in which said spindle is mounted, an offset on said bearing, intermeshing gears on said spindle and in said offset, means for holding a tool in the offset gear and means for supporting said bearing from the work to be operated upon, and allowing longitudinal but preventing angular movement of said bearing in the supporting means. 70

3. A drilling attachment comprising a rotary spindle, a bearing in which said spindle is mounted, an offset on said bearing, intermeshing gears mounted on said spindle and in said offset, tool-receiving means operatively connected with the offset gear, a bracket detachably engageable with the work to be operated upon said bearing being mounted to move longitudinally in the bracket and means 80 in said bracket for preventing other than longitudinal movement of said bearing with respect thereto. 75

4. A drilling attachment comprising a rotary spindle, a sleeve in which said spindle is mounted, an offset on said sleeve, intermeshing gears mounted on said spindle and in said offset, tool-receiving means in the offset gear, a bracket detachably engageable with the work to be operated upon, a boss on said bracket 90 having a cylindric opening adapted to receive said sleeve and a spline common to said sleeve and said boss to prevent their relative rotation. 85

5. A drilling attachment adapted for operating on one flange of a channel-bar or the like, comprising a rotary spindle, a bearing for said spindle, tool-holding means operatively connected to said spindle and offset therefrom to pass between the flanges and a bracket adapted to engage with the other flange of said bar 100 and to form a guide for said bearing. 95

6. A bracket for a drilling attachment comprising a body, a hollow boss, means for detachably and adjustably engaging said body with opposite sides of the bar or like member 105 to be operated upon and means in said boss for preventing other than longitudinal movement of the drilling attachment therethrough.

7. A bracket for a drilling attachment comprising a body constructed to bear against and partially surround the flange of a bar to be operated upon, set-screws at one end of said body adapted to engage with an edge of said flange, a cam at the other end of said body adapted to engage with the opposite edge of said flange, a hollow boss adapted to receive and guide a drill-bearing and means in said boss for preventing other than longitudinal movement of the drilling attachment therethrough. 115
